DIRT AND SNOW MOVER

Frederick B. Arps, New Holstein, Wis.

Application May 10, 1945, Serial No. 592,934

6 Claims. (Cl. 37—155)

1

The present invention relates to an attachment for tractors particularly adapted for use as a scraper for moving or piling dirt or snow or for scraping the dirt or snow and moving it to one side of the driveway.

The principal object of the present invention is to provide a device of the character which can be easily attached and detached from the tractor, easily adjusted for piling or for scraping to one side either snow or dirt and to provide a device which is light and strong and easily manufactured at low cost.

An object of the present invention is to provide a frame including an elongated rearwardly extending element on which the scraper blade holding head is slidably mounted, so it can be differently positioned, longitudinally and having means whereby the blade may be quickly and easily moved to different transverse angles or reversed.

One of the objects of the present invention is to so mount the device on the tractor whereby the blade, particularly when in its rearward position, may be raised a considerable distance above the ground or road surface.

Another object of the present invention is to provide means whereby the blade may be reversed on its supporting bracket for pushing operations as well as pulling.

To these and other useful ends my invention consists of parts, combinations of parts or their equivalents, and mode of operation, as herein-after described and claimed and shown in the accompanying drawings in which:

Fig. 1 is an elevational view of my device attached to a conventional tractor, the near rear wheel of the tractor being removed for obvious reasons.

Fig. 2 is a top view of the device as shown in Figure 1, except having the blade positioned at an angle, and not showing the retaining plates as illustrated in Figure 1.

Fig. 3 is an elevational, partially sectioned view of the attachment with the blade reversed and set at right angles to the tractor for being pushed into the work.

Figs. 4, 5 and 6 illustrate a modification.

In the drawings the tractor is, in its entirety designated by reference character A; the frame of my device is, in its entirety designated by reference character B and the blade holding mechanism in its entirety, is designated by reference character C. Member A may be conventional and supplied with a hydraulic lift which is generally positioned within the frame 10 of the trac-

2

tor having outwardly extending shafts 11—11 which protrude through bearings in frame 10 and have mounted on the ends thereof, arms 12—12, the rear ends of which are operatively connected to draw-bars 13—13 by means of suitable links 14—14, whereby the device may be hydraulically raised, lowered or held in any desired position, in a manner too well known to require further description or illustration.

Frame B comprises preferably, a relatively large tube 20 having secured to its forward end, a depending member 21 preferably, by electric weld as at 22 and having preferably a brace member 23 adapted to strengthen the structure. Member 21 is suitably secured to a transverse tube member 24, to the ends of which the rear ends of members 13 are hingedly mounted as at 25—25.

On the upper forward end of member 20 I secure a post 26 as illustrated, having a brace 27.

These members are preferably electrically welded together and to member 20. The upper end of member 26 is operatively connected to the tractor by means of a link 28 as at 29 and 30; thus member B will be held in its various positions as shown by full and dotted lines in Figures 1 and 2.

It will be seen that because of the relative angles of members 13 and 28, when member B is lifted to its highest position as shown by dotted lines in Figure 1, the scraper blade, particularly when in its rearmost position on member 20, will be moved a considerable distance above the ground; thus clearly the scraper blade may be caused to clear a large accumulation of dirt or snow. However it will be understood that the power lift, being under control of the operator, the height of the blade can be manipulated for leveling and for filling pockets in the road surface.

Member C comprises preferably a tube 40 which is slidably mounted on tube 20, the tube 20 and member 40 having spaced holes for lynchpins 41—41 so member 40 may be held in the position shown in Figures 1 and 2 or in the position shown by dotted lines in Figure 1. It will also be noted that member 40 may be reversed on tube 20 as illustrated in Figure 3 for a purpose which will hereinafter appear.

A plate 42 is preferably electrically welded to member 40 and has openings through which lynchpins 41 extend. These lynchpins may answer as the sole means for holding member 40 in position on member 20. However I may supply two bolts 39—39 for holding member 40 in its desired position. The blade carrying member comprises a plate 43 having a number of openings 47 for the reception of lynchpins 41, these openings

being on a radius with a shaft 44 which is secured to plate 42, preferably by electric welding, the shaft extending freely through plate 43. Plate 43 has secured thereto, preferably by electric welding, a tube 45 and being further secured to plate 43 by means of a brace 46. Tube 45 fits loosely over shaft 44 and a collar 48 is secured to the bottom of shaft 44 for the purpose of holding member 45 and its connecting parts into the position shown in Figures 1 and 3.

Thus it will be seen that members 43, 45 and 46 may be turned to three or more positions on shaft 44 and held in these positions by means of linchpins 41; that in addition to the fore and aft positions made available by simply removing members 41 and bolts 39, member 40 may be removed and reversed.

I provide a scraper blade 50 having preferably removably secured to its lower edge, a cutting and wearing strip 51. Blade 50 is preferably curved, about as shown in Figure 3, the upper edge being flanged as at 52 and suitably secured to member 43, preferably by electric welding, the lower edge being secured to tube 45 by means of a plate 53, preferably by electric weld. I also provide spaced stiffening angle bars 54, their ends being, preferably welded to members 52 and 53.

Thus it will be seen that by removing collar 48, the scraper blade and its connecting parts may be removed. The advantage of this design is that other types of scrapers or earth engaging means may be supplied. It will be seen that for reversing the scraper blade as shown in Figure 3, member C may be removed by simply removing linchpins 41 and bolts 39; or if desired the scraper blade and its connecting parts may be easily removed from shaft 44 and reversed.

In gathering and piling snow and dirt it is frequently desirable to prevent accumulating material from escaping around the ends of the scraper blade and for this purpose I provide plates 55 (see Figure 1) having a shape, about as shown, and being detachably secured in any convenient manner to the ends of the blade.

Figures 4, 5 and 6 illustrate a modification. In this design I illustrate a means for changing the vertical angle of the frame and blade wherein a plate 58 is secured to member 26, having a series of holes 59 to any one of which link 28 may be attached by bolt 29. A sleeve 60 is provided which is secured to member 20 by means of bolts 39, for positioning the head differently, as illustrated in Figure 1. Bars 62 are welded to member 60 as illustrated in Figures 4, 5 and 6 and a plate 64 is welded to bars 62. An opening 66 in plate 64 is provided for a bolt 67 which acts as an axis for the blade holding frame. Bars 62 provide an opening as shown in Figure 6 for the reception of the head of bolt 67.

I provide a plate 68 through which bolt 67 extends, plate 64 is provided with slotted openings 69 at each end and plate 68 is provided with three or more openings 70 at each end, openings 70 being on a radius with bolt 67 as its center. In each opening 69 I provide a bolt 71 having a nut 72 provided, preferably with an extending hand grip 73; thus it will be seen that bolts 71 may be conveniently loosened and moved out of openings 70 so plate 68 may be turned in either direction and securely fastened.

I provide a scraper member 75 which is shaped, about as shown in Figure 4, the upper end 76 extending rearwardly, bolt 67 extending through this member, as shown in Figures 4 and 5. Mem-

ber 76 is preferably securely welded to member 68. At the lower edge of member 75 I secure a blade cutting member 78 having a rearwardly extending flange 79.

I provide spaced brace members 80—80 which are preferably welded to the outer edges of member 68 and to member 76, the bottom edges being welded to member 79, as at 81. These members contact the rear surface of member 75 and are welded thereto. At the ends of members 75, 76, 78 and 79 I provide stiffening braces 82 which are welded thereto, to thereby cooperate with members 80 to form a strong blade supporting unit.

It will be seen that the assembly as shown in Figures 4, 5 and 6 may be moved to different positions on member 20 and that by simply loosening bolts 71 and moving them out of slots 70, the blade may be turned to the right or left.

The advantage of this modified design is that it is simple, light, strong, easily manufactured at low cost and that by simply raising member B the scraper carrying head may be removed, or the scraper blade adjusted to a desired angle or position or reversed on bolt 67 as an axis for use as a bulldozer.

It will be understood that links 14 are easily adjusted as to length so the blade can be angled for terracing or roadway shoulder work and the like. In Figure 2, I illustrate the scraper blade in position for terracing. For this kind of work I secure a land slide plate 85 to the forward end of the blade having a brace 86, plate 85 acting like the land slide of a mold board plow; thus to prevent the side thrust from being transmitted to the tractor or the connecting parts between the blade and tractor.

Having thus shown and described my invention, I claim:

1. In combination with a tractor having a power lift; a frame comprising a rearwardly extending member having at its forward end a transversely extending member and an upwardly extending member, draw-bars hingedly connected at their forward ends to opposite sides of the tractor and at their rear ends to the ends of said transversely extending member, a link pivotally secured at its rear end to the upper end of said upwardly extending member and at its forward end to the tractor, said power lift having an operating connection to said draw-bars for raising and lowering the frame, a head slidably mounted on said rearwardly extending member and means for holding the head in predetermined longitudinal positions, a depending pivotal member secured to said head, another frame rotatably mounted on said pivotal member having a scraper blade and a plate at its upper end adapted to be adjustably engaged by said head, whereby the scraper blade may be turned at various angles transversely.

2. In combination with a tractor having a power lift; a frame comprising a rearwardly extending member having at its forward end a depending member with a transversely extending member on its lower end and an upwardly extending member, draw-bars hingedly connected at their forward ends to opposite sides of the tractor and at their rear ends to the ends of said transversely extending member, a link pivotally secured at its rear end to the upper end of said upwardly extending member and to the tractor at its forward ends, said power lift having an operating connection to said draw-bars for raising and lowering the frame, a head slidably mounted on said rearwardly extending member

and means for holding the head in predetermined longitudinal positions, a depending shaft secured to said head, another frame rotatably mounted on said shaft having a scraper blade and a plate at its upper end adapted to be adjustably engaged by said head, whereby the scraper blade may be turned and held at various angles transversely.

3. In combination with a tractor having a power lift, a longitudinal tube having secured at its forward end an upwardly extending bracket and a downwardly extending member, a transverse member secured midway its ends to the lower end of said downwardly extending member, drawbars hingedly connected at their forward ends to opposite sides of the tractor and at their rear ends to the ends of said transverse member, a link pivotally secured at its rear end to the upper end of said bracket and at its front end to the tractor a distance above said drawbar connections to the tractor, an operating connection from said power lift to said drawbars, a tube shaped head adapted to be adjustably and removably secured to said longitudinal tube and having on its lower side a plate secured thereto, said plate near the center thereof having a downwardly extending bolt, another plate having secured thereto a scraper blade and being substantially the size of said first plate with said downwardly extending bolt extending therethrough and answering as a vertical axis therefor, openings in the forward and rear ends of said plates and being positioned on a radius with said bolt, other bolts extending through said openings whereby the other plate may be locked to the first plate to hold said scraper blade in a transverse or angle position relative to said tube.

4. In combination with a tractor having a power lift, a frame comprising a rearwardly extending tube having at its forward end upwardly and downwardly extending brackets secured thereto, and a transversely extending member secured to the lower end of said downwardly extending bracket intermediate its ends, drawbars hingedly connected at their forward ends to opposite sides of the tractor and at their rear ends to the ends of said transversely extending member, a link pivotally secured at its rear end to the upper end of said upwardly extending bracket and at its forward end to the tractor a distance above said drawbar connections to the tractor, said power lift having an operating connection to said drawbars for raising and lowering the frame, a tube shaped head mounted on said tube and being detachably and adjustably secured

thereto, said tube shaped head having secured to its lower side a plate, another plate rotatably mounted on said first plate, said plates having at their front and rear ends means for securing them together at different angles, a scraper blade rigidly secured to said other plate, said head being slidably mounted on said tube and attachable thereto at different longitudinal positions.

5. A device as recited in claim 4 including, 10 said tube having a length whereby the tube shaped head may be moved to a rearward position, whereby the blade may be reversed on said rotatable mounting as an axis without removing the head from the tube.
- 15 6. In combination with a tractor having a power lift, a tube having secured to its forward end upwardly and downwardly extending members, a transverse member secured intermediate its ends to said downwardly extending member, 20 drawbars hingedly connected at their front ends to opposite sides of the tractor and at their rear ends to the ends of said transverse member, a link pivotally secured at its rear end to the upper end of said upwardly extending member and 25 at its forward end to said tractor, said power lift having an operating connection to said drawbars for raising and lowering said tube, a tube shaped head slidably and rotatably mounted on said tube, means for securing said tube shaped 30 head to said tube in predetermined positions, a plate secured to the under side of said head and having a downwardly and centrally positioned bolt, another plate corresponding substantially in shape with said first plate through which 35 said bolt extends, a scraper blade mounted on said other plate, locking means on the front and rear ends of said plates, whereby the scraper blade may be positioned transverse to said tube or at an angle thereto and firmly locked to the head.

40 FREDERICK B. ARPS.
